APPARATUS FOR PRODUCING ARTISTIC DESIGNS

Filed June 28, 1949

UNITED STATES PATENT OFFICE

2,603,078

APPARATUS FOR PRODUCING ARTISTIC DESIGNS

Louis Jackson, New York, N. Y.

Application June 28, 1949, Serial No. 101,801

1 Claim. (Cl. 68—213)

1

This invention relates to apparatus for producing artistic designs.

In carrying out my process of producing artistic designs with porous materials such as paper, fabric and the like on application of coloring matter to portions of the material and permitting the coloring matter to pass into the absorbent material after portions of the absorbent material have been subjected to the coloring matter and according to the process disclosed in my prior application, Serial No. 788,007, filed November 25, 1947, now Patent No. 2,595,080 granted April 29, 1952, difficulty was had in the subjecting of the portions of the absorbent material with the liquid coloring matter to prevent waves occurring over this area and such as would give an uneven flow of the coloring matter into the absorbent material. These waves were formed and control of the design was more or less lost and the resultant design would have crimped edges.

It is accordingly the principal object of the present invention to provide an apparatus for carrying out my artistic design process wherein the absorbent material will have the coloring liquid passed to the entering areas thereof in an even manner and without the area becoming crimped or buckled and wherein the area surface where the liquid is being applied will remain flat and will be in contact with the applying means throughout its full extent.

It is another object of the present invention to provide apparatus for the carrying out of my process which is constructed to receive bent down edges of the absorbent material and wherein there is provided a pocket containing the coloring liquid for receiving the bent down edges of the absorbent material whereby these edges will be assured of continual contact with the liquid, the pocket being kept filled with the liquid and the edges, which are bent down, being kept immersed in such liquid.

Other objects of the present invention are to provide an apparatus for carrying out my artistic design process wherein the areas of the absorbent material having the coloring matter introduced into it which is of simple construction, inexpensive to manufacture, has a minimum number of parts, easy to permit the adjustment of the absorbent material into it, easy to have the coloring liquid applied to it, compact and efficient in operation.

For other objects and for a better understanding of the invention, reference may be had to the following detailed description taken in connection with the accompanying drawing, in which

2

Fig. 1 is a perspective view of the liquid applying frame forming a part of my apparatus.

Fig. 2 is a sectional view of the frame taken on line 2—2 of Fig. 1.

5 Fig. 3 is a central supporting part for the absorbent material over which the frame is placed for the engagement of the liquid applying strips with the side edges of the absorbent material supported on the central part.

10 Fig. 4 is a perspective view of the apparatus with the absorbent sheet adapted to receive the design therein and in the process of being formed.

Fig. 5 is a transverse sectional view of the assembly as viewed on line 5—5 of Fig. 4.

15 Fig. 6 is a perspective view of a design which has been produced with the apparatus.

Fig. 7 is a fragmentary perspective view of a modified form of apparatus wherein a pocket or channel is provided for receiving a downwardly bent edge of the absorbent sheet.

20 Fig. 8 is a perspective view of an absorbent sheet of irregular shape and having downwardly bent edges which can be treated with the apparatus shown in Fig. 7, an irregular arrangement of 25 the pocket channel being provided in the apparatus to conform to the irregular shape of the absorbent sheet.

Fig. 9 is a layout view of the irregular shape suitably cut to relieve the corners and before the same has been pressed.

30 Fig. 10 is a fragmentary sectional view of a press including a mold and a plunger for forming the irregular shaped sheet of Fig. 8 with downwardly bent edges.

35 Fig. 11 is a view similar to Fig. 10 after the press plate has been extended into the mold recess with the absorbent sheet.

Fig. 12 is a perspective view of an absorbent sheet provided with stopping varnish areas to alter the design and to provide a departure from 40 the general design which would ordinarily be formed on the sheet were the stopping varnish not used.

45 Referring now particularly to Figs. 1 to 6, 15 represents a square frame having a top recess 16 extending peripherally about the frame and adapted to support absorbent soft cotton strips 17, 18, 19 and 20. These soft cotton strips are saturated with a die solution or other coloring matter by pouring on the same from a dispensing bottle 21. Lying within the recess 16 of the frame and under the above cotton strips are other cotton pieces 22.

This frame 15 is adapted to be extended over 55 and receive a slab 24 on which the absorbent

sheet, as indicated at 25, is supported. Non-absorbent elements can be placed under the sheet when on the slab to insure that it is kept free of the top surface of the slab in such a manner as not to interfere with the travel of the liquid through the absorbent sheet. After the frame cotton strips and pieces have been saturated with the coloring solution, the frame with these strips and pieces are extended over the slab so that the pieces will engage with the top surface of the absorbent sheet at the edges thereof. Accordingly, by this apparatus, there will be a certain engagement of the applying strips with the sheet so that the entire edges of the sheet will receive an equal flow per unit length and these edges will be prevented from buckling or becoming elevated. These strips will keep the entire top surface along the edge of the sheet saturated with the liquid. The liquid will move inwardly, as indicated on the sheet, to give the pattern and shading effect indicated at 28. The cotton strips will be in constant contact with the absorbent paper as it begins to form waves or buckle at its edges. After sufficient liquid or solution has been applied to the paper the frame with its cotton strips may be removed by simply lifting it from the slab.

Referring now to Fig. 7, there is shown a modified form of the invention made with the same purpose of providing a constant contact of the edges with the liquid solution passing to the absorbent sheet. A slab 31, similar to the slab 24, is provided for this purpose. A groove or channel pocket 32 extends around the slab and on the inner face thereof. A sheet 33 is prepared with down turned edges 34. Within the groove there is applied solution 35 and the down turned edges of the sheet will become completely immersed in the liquid so that the liquid is evenly distributed throughout the edges of the sheet. This arrangement has particular application where the sheet is to be of irregular shape, as for example as shown in Fig. 8. The groove would then be cut in the slab according to the shape of the irregular figure. The irregular figure is indicated at 36 and is made from a previously cut blank 37. The blank 37 is cut to the general shape of the sheet to be desired and to be fitted to a particular board or slab that is to be used and on the curved edges and at the corners there is provided slits 38 to prevent the cut blank from tearing when the same is finally formed with turned down edges 39.

With the blank cut as viewed in Fig. 9, it can be placed on a mold 41 over a recess 42 and adjusted to a guide or stop 43 serving to properly position the same and beneath a press plate 44 adapted to fill the recess and to form the bent edges 34, Fig. 11, as the press plate is finally allowed to fill the recess 42.

If desired, the sheets of absorbent material may be provided with stop lines 45, Fig. 12, which are formed by the coating of the sheet at these locations with a varnish tending to close the pores of the material and to prevent the liquid from passing through the pores at these locations.

The liquid moving inwardly from the edges of the sheet will accordingly be obliged to follow the stop lines 45 and enter the inner portions of the sheet only through passages 46 and 47 which are permitted because of the spacing of the stop coating 45. These stop coatings will accordingly provide and make possible other types of designs or figures in the absorbent sheet.

The designs which are constructed according to this new process and with the above described apparatus can be put to numerous uses. These designs have use on textile fabrics, scarves, neckties, can be framed and hung on walls as wall decorations, lamp shades, and various other uses. 15 While various changes may be made in the detail construction, it shall be understood that such changes shall be within the spirit and scope of the present invention as defined by the appended claim.

20 What is claimed is:

An apparatus for forming designs upon absorbing material with coloring solutions which comprises a slab to support a sheet of absorbent material of a similar shape, a frame encompassing said slab and the absorbent sheet that would be supported thereupon, said frame having a recess extending around the top thereof for receiving the coloring solution, and an absorbent mass surrounding the top of the frame and dipping into said recess containing the coloring solution, said absorbent mass extending inwardly over the edges of the slab and adapted to overlie the edges of the absorbent sheet to be colored and that may be supported upon the slab, whereby the coloring solution will be transmitted to the edges of the absorbent sheet being treated and upon the frame being fitted over the slab, said frame with the absorbent mass being removable from the slab and the absorbent sheet in order that the treating action of the absorbent sheet with the solution can be easily discontinued at the will of the operator.
